TACK BUTTON

Franklin R. White, Waterbury, Conn., assignor to
 The Patent Button Company, Waterbury,
 Conn., a corporation of Connecticut

Application November 2, 1934, Serial No. 751,209

3 Claims. (Cl. 24—95)

My invention relates to new and useful improvements in tack buttons, and has for an object to provide a button that is relatively cheap to manufacture and durable in service.

5 As is well known, tack buttons consist of the button head proper, a number of which are placed in the hopper of a button attaching machine while tacks are placed in a separate hopper, and the positioning of each button head on the machine is synchronized with the forcing of a tack up through the material to which the button is to be attached and into the button head, the tack head being curled or deformed within the button head during the attaching operation to thus form a permanent fastening of the button to the cloth.

The present button is somewhat similar in its broadest aspects to the button shown in Patent No. 1,744,350, granted to Franklin R. White, Leonard 20 R. Carley, and Walter T. Abel, in that the button includes a shell or button back, anvil, and cap, the lower extremity of the hub being somewhat flared, so that the material of the deformed tack may occupy the enlarged portion of the hub to 25 thus more tightly hold the button.

However, I have found that it would be advantageous to provide an additional reinforcement in the lower extremity of the hub, which reinforcement will permit of a better cooperation 30 of the tack with the button head and will also act as a proper guide for the tack in passing through the hub of the button head and thus provide a more uniform curling or deforming of the tack within the head.

35 It will be understood that the shell or button back is of relatively thin material and there is a possibility of the tack being not properly aligned when passing through this relatively thin material of the button back.

40 One of the objects, therefore, of the present invention is to provide a relatively thin button back or shell and to provide an anvil, sometimes called a slug, for curling or deforming the tack on attaching the button. Also there is additionally provided a hard metal reinforcement which is jammed tightly within the hub, which jamming will, in turn, increase slightly the diameter of the hub at its lower end. This reinforcement will tend to properly guide the tack on its way to the 45 anvil and furthermore hold the hub or shank of the tack in its vertical position during the deformation or curling of the point of the tack which, of course, occurs when the tack contacts with the anvil or slug.

55 With these and other objects in view, the in-

vention consists in certain new and novel features and combination of parts, as will be hereinafter more fully explained and pointed out in the claims.

Referring now to the drawing showing a preferred embodiment of my invention and two slight modifications of slugs or anvils,

Fig. 1 is an enlarged sectional view of my improved button showing the reinforcing plate within the now enlarged lower end of the hub 10 and showing a fragmentary portion of the cloth to which the button is to be attached and the tack directly beneath the button head;

Fig. 2 is a side elevation of the button after being attached to the cloth;

Fig. 2a is a cross sectional view similar to Fig. 2;

Fig. 3 is a bottom plan view of the button with the hub partly broken away to expose the reinforcing plate;

Fig. 4 is a sectional view of the button shell 20 or back before the reinforcing plate is in final position;

Fig. 5 is a view of the button shell with the reinforcing plate in position and after the same has been jammed in the hub and pierced;

Fig. 6 is a slightly modified form of anvil;

Fig. 7 is a still further slightly modified form of anvil; and

Fig. 8 is a perspective view of the reinforcing plate or disc.

Referring now more particularly to the several views and for the moment to Fig. 4, there is shown the button back comprising what I term the body 1, the outwardly extending flange 2, and the slightly tapered hub 3. This shell is 35 formed of relatively thin metal and is so far conventional in construction.

Referring for the moment to Fig. 5, there will also be seen the button back or shell but in this instance there is shown the reinforcing plate 4 40 having been forced within the lower end of the hub 3, the reinforcing plate 4 thus being held against movement within the shell.

It will be understood that the hub of the button is slightly tapered so that when a reinforcing plate, which is larger than the diameter of the lower extremity of the hub, is dropped in, it will come to rest at a point above the bottom wall of the hub. However, pressure is then applied to the reinforcing plate to jam the same downwardly to the bottom of the hub, which jamming action will cause it to be enlarged or swaged and also increase the diameter of the bottom of the hub to tightly grip the reinforcing plate and hold the same in position.

The next operation is to pierce the bottom of the hub and the reinforcing plate, as shown in Fig. 5.

As may be clearly seen in Fig. 5, the hub has the crimped or rolled appearance, as at 5, after the reinforcing plate 4 is jammed in position. Then the hub of the button head is pierced so that there will be the opening 6 and also the small registered opening 6' in the reinforcing plate 4.

This reinforcing plate 4 is preferably made of relatively hard metal so that the side walls of the opening 6, 6' will act as a proper guide when the tack is inserted, as will shortly be described.

Now glancing at Fig. 1 for the moment, there may be seen mounted within the hub of the button the anvil or, as it is sometimes spoken of, the slug 7, which is also of relatively hard metal and is cut out in a circular manner at its lower end to form the chamber 8 with the slightly constricted opening 8a, while the body portion extends outwardly, as at 9, overlying the body 1 of the button. This anvil or slug having the slightly constricted mouth will allow the tack to properly enter the chamber 8 and guide the tack point during its deformation.

Then crimped over the flange 2 is the cap 10 which may have any raised insignia 11 thereon as desired. Ornamented caps are no novelty so a further description of the same is not thought necessary.

In Fig. 1, there is also shown a tack 12 and the shank 13 is to be driven up into the button head and deformed, as shown in Fig. 2a.

As heretofore mentioned, these tack buttons are always attached in what is known as a button attaching machine and a plunger (not shown) will force the button head down against the cloth while a tack being in position will be forced through the small opening 6 of the hub and guided in its upward movement by the side walls of the opening 6' within the reinforcing plate 4. A portion of the shank 13 will then be deformed, as shown at 14 in Fig. 2a, due to its being jammed against the anvil and will extend downwardly and overlie and closely contact the reinforcing plate 4, thus tightly clamping the button head to the material 15 to which the button is shown as attached.

It will be seen that by providing this reinforcing plate, there is no likelihood of the tack not being properly centered or properly positioned with respect to the button head as the shank of the tack will be guided by the side walls of the opening and until the tack point contacts with the upper wall of the circular formation in the anvil.

In Fig. 6, I have shown a slightly modified anvil 7a and in this instance it will be noticed that the chamber is slightly deeper in the anvil while the mouth or entrance to the chamber is not constricted. Likewise, in the modified form shown

in Fig. 7, the anvil 7b has the chamber 7c but in this instance the chamber is substantially hemispherical in form.

It will be understood, however, that I prefer in most instances to use the anvil as shown in the preferred form, as the constricted opening has a tendency to more perfectly guide the tack in its deformation during the attaching period.

I am aware that in the patent to Ford, No. 1,873,372, there is shown a small disc but it 10 will be understood that this disc in reality is a fastener engaging element and not a reinforcing plate in any sense of the word, as the hub in this Ford button would be entirely open if this plate were not in position.

Having thus described my invention, what I claim as new and desire to secure by Letters Patent is:

1. A tack button comprising a shell, said shell having an upwardly extending peripheral rim, 20 a hub tapering slightly toward its lower extremity which latter is slightly enlarged, a metal reinforcing perforated disc held tightly within the enlarged extremity of the hub, an anvil located in the hub and at its lower portion bearing 25 against said metal reinforcing perforated disc, a cap over said anvil and the rim of the shell, the said metal reinforcing perforated disc adapted to properly guide the prong of a tack to the anvil, and the anvil adapted to turn the prong of the 30 tack downwardly and against the said metal reinforcing perforated disc.

2. A tack button comprising a shell, said shell formed of relatively soft metal and having an upwardly extending peripheral rim, an integral hub 35 having a slightly enlarged lower extremity, a hard metal reinforcing perforated disc clamped within the enlarged extremity of the hub, an anvil of relatively hard metal also located in the hub and having a chamber therein with a re- 40 stricted opening above the opening in the perforated disc, a cap on said button shell, the hard metal reinforcing perforated disc and the anvil adapted to guide and deform a tack within the 45 chamber during an attaching operation. 45

3. A tack button comprising a shell, said shell formed of relatively soft metal and having an upwardly extending peripheral rim, an integral hub having a slightly enlarged lower extremity, a reinforcing perforated disc of relatively hard 50 metal clamped within said enlarged extremity, an anvil having a chamber with a restricted opening in said hub, a cover over said shell, the anvil adapted to mutilate the prong of a tack and deform the same down against the reinforcing perforated disc, and the reinforcing perforated disc adapted to properly guide the tack to the chamber in the anvil.

FRANKLIN R. WHITE.
